UNITED STATES PATENT OFFICE.

WILLIAM H. ROBERTSON, OF TORONTO, ONTARIO, CANADA.

DEVICE FOR STOPPING LEAKS IN WATER-PIPES.

SPECIFICATION forming part of Letters Patent No. 327,899, dated October 6, 1885.

Application filed March 23, 1885. Serial No. 159,757. (No model.)

To all whom it may concern:

Be it known that I, WILLIAM HUTCHINSON ROBERTSON, a subject of the Queen of Great Britain, residing at Toronto, in the county of 5 York, Province of Ontario, Canada, have invented certain new and useful Improvements in Devices for Stopping Leaks in Lead Pipes; and I do hereby declare that the following is a full, clear, and exact description of the 10 same.

My invention has relation to a device for the more effectual closing of breaks in lead pipes, whereby a perfectly secure water-tight joint is secured with the least possible expense, 15 and without the necessity of calling in the services of a plumber; and it consists of an ordinary clamp, in which fit top and bottom elongated cups having sharp-cutting edges, which grasp the pipe, and, owing to the pressure of the clamp, enter the surface of the pipe 20 all round said edges, and secure a perfectly water-tight joint.

In the drawings, Figures 1 and 2 are front and side views, respectively, of my device, 25 with the pipe inserted. Fig. 3 is a view of one of the elongate cups.

A is the clamp cast or constructed in the ordinary way.

B is a pipe which we suppose to have been 30 burst.

C is the bottom cup, and D the top one. The bottom cup is inserted in the seat E of the clamp, which is then brought to the pipe, and the top clamp is then placed on the side

of the pipe, so as to cover the crack or burst, 35 when the screw is turned, and, the top cup forced, its sharp edges *a*, as well as the sharp edges of the bottom cup, commence to enter the exterior surface of the pipe, and continued pressure will drive the cutting-edges 40 home until it is impossible for any water to escape, no matter what pressure is exerted. It will be observed that as both cups are constructed in precisely the same manner, they both act alike, and it is immaterial which is applied first.

b and *c* are notches. If it is desired to remove the clamp for another leak, wire may be bound round these notches, effectually securing the cups to the pipes.

What I claim as my invention is—

1. In a device for stopping leaks in pipes, the combination, with a clamp, A, provided with a screw and formed with a seat, E, of cups C and D, one of said cups fitting in the 55 seat of the clamp, and the other adapted to have the screw bear against it, and both formed with sharp edges *a*, substantially as described.

2. A device for stopping leaks in pipes, consisting of the two elongated cups C and D, 60 formed with sharp edges on their inner faces to enter a pipe, and having notches *b* and *c* on their exterior faces, substantially as and for the purpose described.

W. H. ROBERTSON.
